ABSTRACT

A new *Chrysanthemum* plant named 'Synwil Yel' particularly distinguished by the medium to large inflorescences with yellow colored ray florets, dark yellow-green foliage, good compact mounded habit, and a natural flowering season in later September.

1 Drawing Sheet

1

Latin name of the genus and species of the plant claimed:
Chrysanthemum×morifolium.
Varietal denomination: 'Synwil Yel'.

BACKGROUND OF THE NEW PLANT

The present invention comprises a new *Chrysanthemum*, botanically known as *Chrysanthemum×morifolium*, and hereinafter referred to by the variety name 'Synwil Yel'.

'Synwil Yel' is a product of a planned breeding program. The new cultivar has medium to large inflorescences with yellow colored ray florets, dark yellow-green foliage, good compact mounded habit, and a natural flowering season in later September.

'Synwil Yel' originates as a natural whole plant mutation of 'Yowilma', U.S. Plant Pat. No. 18,924. 'Synwil Yel' was discovered outdoor in a large quantity trial format and selected by the inventor as a single flowering plant within a population of the parent cultivar in a controlled breeding program in Alva, Fla. in November 2006. The parent cultivar 'Yowilma' has white flower color and is somewhat of a faster flowering response in both shaded and natural season crops.

The first act of asexual reproduction of 'Synwil Yel' was accomplished when vegetative cuttings were propagated from the initial selection in December 2006 in a controlled environment in Alva, Fla.

BRIEF SUMMARY OF INVENTION

Horticultural examination of plants grown from cuttings of the plant initiated in December 2006, and continuing thereafter, has demonstrated that the combination of characteristics as herein disclosed for 'Synwil Yel' are firmly fixed and are retained through successive generations of asexual reproduction.

'Synwil Yel' has not been observed under all possible environmental conditions. The phenotype may vary significantly with variations in environment such as temperature, light intensity and day length.

2

A Plant Breeder's Right for this cultivar was applied for in Canada on Oct. 30, 2009 (09-6772). 'Synwil Yel' has not been made publicly available more than one year prior to the filing of this application.

The following traits have been repeatedly observed and are determined to be basic characteristics of the new variety. The combination of these characteristics distinguishes this *Chrysanthemum* as a new and distinct variety.

BRIEF DESCRIPTION OF THE PHOTOGRAPHS

10 The accompanying photographic drawing shows typical flower and foliage characteristics of 'Synwil Yel' with colors being as true as possible with an illustration of this type. The photographic drawing shows a flowering potted plant of the new variety, and a close-up of the flowers.

DETAILED BOTANICAL DESCRIPTION

15 The plant descriptions and measurements were taken in Gilroy, Calif. in August 2009 under natural light. These plants were about 10 weeks old. The aforementioned photographs were taken in Gilroy, Calif. in late October 2009 outdoors. These plants were approximately 12 weeks of age.

20 Color references are made to The Royal Horticultural Society Colour Chart (R.H.S.) 2001.

TABLE 1

25 DIFFERENCES BETWEEN THE NEW VARIETY 'SYNWIL YEL'
AND A SIMILAR VARIETY: 'MERMAID YELLOW IMPROVED'
(U.S. Plant Pat. No. 18,905)

	'Mermaid Yellow Improved' (U.S. Plant Pat. No. 18,905)	'Synwil Yel'
Ray floret color:	RHS 3A	RHS 8A
Inflorescence diameter:	Smaller	Larger
Natural season flowering response:	1 week faster	1 week slower

30 Plant:

40 *Form, growth and habit.*—Herbaceous decorative garden-type; stems upright and outwardly spreading, freely branching, strong and moderately vigorous growth habit.

<i>Plant height.</i> —20-22 cm.		<i>Lower surface.</i> —Between RHS 3C and RHS 3D.
<i>Plant height (inflorescence included).</i> —22-24 cm.		<i>Mature inflorescence:</i>
<i>Plant width.</i> —34-37 cm.		<i>Diameter.</i> —4.8-5.2 cm.
<i>Garden performance and tolerance to weather.</i> —Very good.	5	<i>Depth.</i> —2.0-2.5 cm.
<i>Roots:</i>		<i>Total diameter of 'disc'.</i> —No disc showing.
<i>Number of days to initiate roots.</i> —4 days at about 22 degrees C.		<i>Receptacle height.</i> —0.4-0.5 cm.
<i>Number of days to produce a rooted cutting.</i> —10-12 days at 22 degrees C.	10	<i>Receptacle diameter.</i> —0.4-0.5 cm.
<i>Type.</i> —Fine, fibrous, free branching.		<i>Ray florets:</i>
<i>Color.</i> —RHS N155B but whiter.		<i>Average quantity of florets.</i> —175 in numerous whorls.
<i>Foliation:</i>		<i>Color of florets, upper surface.</i> —RHS 3A.
<i>Arrangement.</i> —Alternate, simple.		<i>Lower surface.</i> —RHS 3C.
<i>Immature, leaf color, upper surface.</i> —RHS 147A.	15	<i>Length.</i> —2.1-2.9 cm.
<i>Lower surface.</i> —Closest to RHS 137A.		<i>Width.</i> —0.55-0.7 cm.
<i>Mature, leaf color, upper surface.</i> —RHS 147A.		<i>Shape.</i> —Oblong.
<i>Lower surface.</i> —Closest to RHS 137A.		<i>Apex shape.</i> —Obtuse to slightly retuse or even emarginate.
<i>Length.</i> —3.2-4.0 cm.	20	<i>Margin.</i> —Entire.
<i>Width.</i> —2.8-3.2 cm.		<i>Texture, upper surface.</i> —Papillose.
<i>Shape.</i> —Ovate.		<i>Lower surface.</i> —Papillose.
<i>Base shape.</i> —Attenuate.		<i>Disc florets:</i>
<i>Apex shape.</i> —Mucronulate.		<i>Average quantity of florets.</i> —Sometimes 1.
<i>Margin.</i> —Palmately; irregularly lobed; irregularly serrate.	25	<i>Color of florets.</i> —RHS 147D.
<i>Texture, upper surface.</i> —Bifid T-shaped hairs.		<i>Length.</i> —0.1 cm.
<i>Lower surface.</i> —Heavily Bifid T-shaped hairs.		<i>Width.</i> —0.2 cm.
<i>Color of veins, upper surface.</i> —Closest to RHS 147A.		<i>Shape.</i> —Tubular, elongated.
<i>Color of veins, lower surface.</i> —RHS 137B.		<i>Apex shape.</i> —Acute, 5 pointed.
<i>Petiole color.</i> —Closest to RHS 147A.	30	<i>Phyllaries:</i>
<i>Length.</i> —0.9-1.2 cm.		<i>Quantity.</i> —20-25.
<i>Diameter.</i> —0.2 cm.		<i>Color, upper surface.</i> —Closest to RHA 137A.
<i>Texture.</i> —Heavily Bifid T-shaped hairs.		<i>Lower surface.</i> —Closest to RHS 147A but appears more grey due to hairs.
<i>Stem:</i>		<i>Length.</i> —0.4-0.6 cm.
<i>Quantity of main branches per plant.</i> —About 20.	35	<i>Width.</i> —0.15-0.2 cm.
<i>Color of stem.</i> —Closest to RHS 147B but a little greener.		<i>Shape.</i> —Lanceolate.
<i>Length of stem.</i> —19-22 cm.		<i>Apex shape.</i> —Acute.
<i>Diameter.</i> —0.3 cm.		<i>Based.</i> —Fused.
<i>Length of internodes.</i> —1.5-3.5 cm.	40	<i>Margins.</i> —Entire; papery.
<i>Texture.</i> —Heavily Bifid T-shaped hairs.		<i>Texture, upper surface.</i> —Smooth and glossy.
<i>Color of peduncle.</i> —Closest to RHS 147B.		<i>Lower surface.</i> —Heavily bifid T-shaped hairs.
<i>Length of peduncle.</i> —5.0-6.0 cm.		<i>Reproductive organs:</i>
<i>Peduncle diameter.</i> —0.25-0.3 cm.	45	<i>Pistil.</i> —1.
<i>Texture.</i> —Heavily Bifid T-shaped hairs.		<i>Found on both florets.</i> —Yes.
<i>Inflorescence:</i>		<i>Length.</i> —0.4-0.5 cm.
<i>Type.</i> —Composite type, solitary inflorescences (decorative-type) borne terminally above foliage, ray florets arranged acropetally on a capitulum.		<i>Style color.</i> —RHS 1B.
<i>Natural season flowering.</i> —Late September.	50	<i>Style length.</i> —0.4 cm.
<i>Quantity of inflorescences per plant.</i> —About 60 open flowers and 100-125 buds.		<i>Stigma color.</i> —RHS 1B.
<i>Lastingness of individual blooms on the plant.</i> —About 4 weeks.		<i>Stigma shape.</i> —Bi-parted.
<i>Fragrance.</i> —Slightly spicy.	55	<i>Ovary color.</i> —RHS 155C.
<i>Bud (just when opening/showing color):</i>		<i>Stamens.</i> —1.
<i>Color.</i> —RHS 4C.		<i>Found on disc florets only.</i> —Yes.
<i>Length.</i> —1.0-1.5 cm.		<i>Color of filaments.</i> —RHS 1C.
<i>Width.</i> —1.0 cm.		<i>Length filaments.</i> —2.0 cm.
<i>Shape.</i> —Oblate.		<i>Anther color.</i> —RHS 6C.
<i>Immature inflorescence:</i>		<i>Anther length.</i> —0.15 cm.
<i>Diameter.</i> —3.0-3.6 cm.		<i>Anther shape.</i> —Oblong.
<i>Color of ray florets, upper surface.</i> —RHS 2A but brighter.		<i>Color of pollen.</i> —RHS 7A.
		<i>Pollen amount.</i> —Moderate.
		<i>Fertility/seed set.</i> —Has not been observed on this hybrid.
		<i>Disease/pest resistance:</i> Disease/pest resistance has not been observed on this hybrid.
		<i>What is claimed is:</i>
	60	1. A new and distinct variety of <i>Chrysanthemum</i> plant named 'Synwil Yel' substantially as illustrated and described herein.
